UNITED STATES PATENT OFFICE.

CHARLES H. DOKE, HARRY E. BERRY, DANIEL H. DELZELL, AND CHARLES A. DELZELL,
OF DENVER, COLORADO.

DESIGN FOR A MILITARY EMBLEM, BADGE, OR BUTTON.

50,937.

Specification for Design.

Patented June 19, 1917.

Application filed June 12, 1916. Serial No. 103,337. Term of patent 3½ years.

To all whom it may concern:

Be it known that we, CHARLES H. DOKE, HARRY E. BERRY, DANIEL H. DELZELL, and CHARLES A. DELZELL, citizens of the United States, and residents of the city and county of Denver, State of Colorado, have invented a certain new, original, and ornamental Design for a Military Emblem, Badge, or Button, of which the following is a full, clear, and exact description, reference being had to the accompanying drawing, forming a part hereof.

In this drawing, the figure is an elevation view of the emblem, badge, or button.

Copies of this patent may be obtained for five cents each, by addressing the "Commissioner of Patents, Washington, D. C."

We claim:

The ornamental design for a military emblem, badge, or button, as shown.

In testimony whereof, we affix our signatures in the presence of two witnesses.

CHARLES H. DOKE.
HARRY E. BERRY.
DANIEL H. DELZELL.
CHARLES A. DELZELL.

Witnesses:

FELIX THIES,
JNO. G. POWELL.
